UNITED STATES PATENT OFFICE.

GEORGE L. PIERCE, OF BROOKLYN, NEW YORK, ASSIGNOR TO A. G. SPALDING & BROS.
MFG. CO., OF JERSEY CITY, NEW JERSEY, A CORPORATION OF NEW JERSEY.

FOOT-BALL HEAD-HARNES.

1,200,130.

Specification of Letters Patent.

Patented Oct. 3, 1916.

Application filed June 12, 1916. Serial No. 103,133.

To all whom it may concern:

Be it known that I, GEORGE L. PIERCE, a citizen of the United States, and resident of Brooklyn, New York, have invented certain 5 new and useful Improvements in Foot-Ball Head-Harness, of which the following is a specification.

The invention is an improvement upon that disclosed in Letters Patent of the 10 United States granted to me, No. 694,986, and it consists in the features and combination and arrangement of parts hereinafter described and particularly pointed out in the claims.

15 In the accompanying drawings Figure 1 is a sectional view of the harness, and Fig. 2 is a sectional view looking from the underside of the head-harness.

In these drawings 1 indicates the outer 20 shell or member of the harness, which may be of any suitable construction, but in the particular form illustrated it consists of a cap-like member 2 with crossing strips 3 sewed thereto, these strips 3 being made of 25 comparatively stiff leather stitched to the member 2. The inner shell or member 4, which is spaced apart from the outer shell at its top, but is connected thereto at its lower edge, consists, in my present invention, 30 of a series of strips 5 radiating from the center of this inner shell or member, and, while these strips may be of any suitable material and may be arranged in various ways, I prefer to connect them at the central portion of 35 the member where they converge with each other. I prefer to form these strips of suitable length to extend in arched form from the lower edge of the outer reinforced shell on one side to the lower edge of said outer 40 shell on the other side, each strip being continuous from end to end and overlapping, or underlapping, as the case may be, the other diametrically disposed strips. These strips, where they lap one upon the other 45 at the central portion, may be secured in various ways, but I prefer to employ a disk 6 of suitable material with circular rows of stitching 7 passing therethrough and through the radiating strips. The central member or 50 disk may be formed of leather and I prefer to form the strips of textile fabric. An appropriate amount of space is left between the crown of the inner member, or shell, and the crown of the outer member to afford

protection to the head of the wearer, it being 55 understood that the harness will be supported on the head by contact of the inner member therewith. This is flexible to accommodate itself to the shape of the head, and being formed of strips, as described, spaces of 60 considerable area are left at 8 between the strips, these spaces gradually enlarging from the center outwardly to the lower edge of the outer shell, and this divided formation of 65 the inner shell also enables it to accommodate itself to the shape of the head, as well as providing for a high degree of ventilation, the outer stiff shell being provided with 70 perforations 9 for the passage of air. The outer ends of the radiating strips are secured 75 to the reinforced outer shell, preferably, by stitching 10 passing around the lower portion of the outer shell; and this stitching also serves to hold a band of felt, or other material shown at 11, which extends around 80 the interior of the outer shell at the lower edge thereof, this band covering the outer ends of the radiating strips of the inner shell or member. Suitable felt lining, indicated at 12, is connected by adhesive ma- 85 terial to the inner side of the outer reinforced shell and the covering strip of felt, or like material, may be secured by adhesive to this felt or cotton batting lining of the outer shell. The harness is provided with 90 the skirt portion 13, and the band 14 at the front connected by elastic at 15 with the skirt portion, and this band and the skirt portion are secured to the cap portion by stitching them to the ends of the reinforcing 95 strips 3. The skirt portion may have the usual ear protectors 16.

The outer member, as above stated, is reinforced by the crossing strips 3, and this outer member is lined with soft felt. This 95 construction while providing an outer member which is comparatively stiff as regards the inner member composed of the flexible crossing strips of textile fabric provides a 100 construction which will meet the requirements of intercollegiate foot ball rules because a structure like that described will not be dangerous to the opponents of the wearer, the outer shell providing contact surfaces or areas which are sufficiently soft to avoid 105 damage to the opposing players who come in violent contact with the head gear. At the same time the outer shell, because of the re-

inforcing derived from the crossing strips 3, will be sufficiently resistant to avoid damage to the wearer of the head gear.

I claim as my invention:—

5. 1. In combination in a head-harness, an outer shell reinforced by exterior strips crossing each other and sewed thereto and an inner member composed of strips of textile fabric extending in arched form from
- 10 side to side of the outer shell and connected thereto, said inner member being spaced apart from the outer shell, substantially as described.
- 15 2. In combination in a head-harness, an outer shell, an inner member composed of strips of textile fabric radiating from the crown of the inner member and extending downwardly to the lower edge of the outer shell and a band of soft material overlying
- 20 the lower ends of the said textile strips, said inner member being spaced apart from the shell, substantially as described.
- 25 3. In combination in a head harness, an outer shell, an inner member composed of strips of textile fabric radiating from the

crown of the inner member and extending downwardly to the lower edge of the outer shell and a band of soft material overlying the lower ends of the said textile strips, said inner member being spaced apart from the shell, and said band of soft material being secured to the shell by a line of stitches, which also secures the ends of the radiating strips to the said shell, substantially as described.

30 4. In combination in a head harness, an outer shell composed of a cap-like member stiffened by crossing strips attached thereto, said member having a soft lining of felt, and an inner member attached to the lower portion of the outer member and consisting of crossing strips spaced apart from the outer member intermediate of their attached ends, substantially as described.

35 In testimony whereof, I have affixed my signature.

GEORGE L. PIERCE.
